(57) **CLAIM**

The ornamental design for a VR headwear, as shown and described.

DESCRIPTION

FIG. 1 is a top perspective view of a VR headwear, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a left side perspective view of another stereogram, but with a different broken line;

FIG. 9 is a left side perspective view showing the VR headwear in an exemplary configuration of use;

FIG. 10 is a left side perspective view showing the VR headwear in an exemplary configuration of use;

FIG. 11 is a left side perspective view showing the VR headwear in an exemplary configuration of use;

FIG. 12 is a left side perspective view showing the VR headwear in an exemplary configuration of use; and,

FIG. 13 is a left side perspective view showing the VR headwear in an exemplary configuration of use.

The broken lines in the drawings illustrate the portions of the VR headwear, which form no part of the claimed design.
